UNITED STATES PATENT OFFICE.

TRUEL T. LEE, OF YARMOUTH, IOWA.

DESIGN FOR A BUTTON-FASTENER.

49,997.

Specification for Design.

Patented Dec. 5, 1916.

Application filed October 5, 1916. Serial No. 123,991. Term of patent 14 years.

To all whom it may concern:

Be it known that I, TRUEL T. LEE, a citizen of the United States, residing at Yarmouth, in the county of Des Moines, State of Iowa, have invented a new, original, and ornamental Design for Button-Fasteners, of which the following is a specification, reference being had to the accompanying drawing, forming a part thereof.

The figure is a perspective view of a button fastener showing my new design.

I claim:

The ornamental design for a button fastener as shown.

TRUEL T. LEE.

Witnesses:

DAVID MICHAELS,
H. F. CRAIG.
